UNITED STATES PATENT OFFICE.

THADDEUS A. SPRADLEY, OF CROPWELL, ALABAMA.

DOOR-LOCK.

1,130,034.

Specification of Letters Patent.

Patented Mar. 2, 1915.

Application filed September 16, 1913. Serial No. 790,111.

To all whom it may concern:

Be it known that I, THADDEUS A. SPRADLEY, a citizen of the United States, residing at Cropwell, in the county of St. Clair and State of Alabama, have invented new and useful Improvements in Door-Locks, of which the following is a specification.

This invention relates to improvements in door locks and has particular application to a sliding door lock.

In carrying out the present invention, it is my purpose to provide a sliding door lock which will embody among other features jaws pivoted upon a common center scissors fashion and movable to open and closed positions about such center, and a keeper adapted to be engaged by the jaws when the door equipped with the lock is moved to closed position.

It is also my purpose to provide a sliding door lock which will embrace the desired features of simplicity, efficiency and durability, one which may be manufactured and marketed at a minimum expense and one which may be readily and conveniently operated.

With the above and other objects in view, the invention consists in the construction, combination and arrangement of parts hereinafter set forth in and falling within the scope of the claim.

In the accompanying drawing; Figure 1 is a view in side elevation of a sliding door lock constructed in accordance with my present invention, one side plate of the casing being removed and the parts shown in locking position. Fig. 2 is a sectional view on the line 2—2 of Fig. 1 looking in the direction of the arrow. Fig. 3 is a perspective view of the jaws removed from the casing.

Referring now to the accompanying drawing in detail, the numeral 1 designates a lock casing constructed of any suitable material and preferably of rectangular outline. This casing is adapted to be connected with a sliding door in any suitable manner and is provided interiorly with a vertical plate 2 spaced apart from the forward end wall of the casing and in parallelism therewith, the forward end wall being formed with an entrance opening 3.

4, 5 designate the jaws of the lock each comprising arms 6, 7 offset from each other and having the adjacent ends connected with a hub 8 formed with a bore 9. The hub 8 of the jaw 5 has one face thereof cut out so as

to receive the hub of the other jaw and when the jaws are assembled the bores 9, 9 in the hubs thereof register with each other to receive a horizontal pivot bolt 10 carried by one of the side walls of the casing 1 approximately centrally thereof. When the jaws are assembled, the rear arm 7 of the lower jaw 5 overlies the rear arm 7 of the upper jaw, while the arm 6 of the upper jaw 4 overlies the similar arm of the lower jaw 5 incident to the arms of each jaw being offset from each other and connected with the hub. The forward arms 6, 6 of the jaws are adapted to work within a slot formed in the plate 2 and the confronting faces of such arms at the forward ends thereof are formed to provide hooks 11, 11 coöperating with each other to receive and hold the arrow shaped head 12 of the stationary keeper 13. Substantially inclosing the rear ends of the arms 7, 7 of the jaws is a U-shaped yoke 14 having the free end of the opposite limbs thereof outturned to provide securing flanges 15, 15 whereby the yoke may be fastened to one side wall of the casing 1. Projecting outwardly from the interconnecting member of the yoke approximately centrally thereof is a barrel 15 within which is rotatably mounted a shank 16 carrying a cam 17 disposed between the contacting edges of the arms 7, 7 of the jaws and working within cavities 18, 18 formed in such edges of the arms. Projecting outwardly from the opposite side of the cam 17 coaxial with the shank 16 is a stud 19 rotatably mounted within a bearing carried by the inner surface of the adjacent side wall of the casing and coöperating with the barrel 15 to support the cam. Normally, the jaws are held in closed position and for this purpose I employ, in the present instance, a coiled spring 20 encircling a pin 21 carried by the casing between the arms 6, 6 of the jaws immediately adjacent to the pivot point thereof, the opposite extremities of the spring 20 extending outwardly and bearing upon the outer edges of the arms 6, 6 of the jaws to hold the latter normally closed.

From the foregoing description taken in connection with the accompanying drawing, the construction, mode of operation and manner of employing my invention will be readily apparent. When the door equipped with my improved lock slides to closed position, the arrow head 12 of the keeper 13 enters the casing by way of the opening 3

therein and passes between the hooks 11, 11 on the respective ends of the arms 6, 6 of the jaws 4, 5 and in passing the hooks the jaws are swung about the pivot bolt 10 5 against the action of the spring 20 so that the arrow head of the keeper may pass behind the hooks and so lock the door against opening movement, the spring restoring the jaws to locking position. When it is desired to open the door, a key is engaged 10 with the shank 16 and the latter rotated within the barrel 15 so that the active surfaces of the cam 17 engage the cavities 18, 18 in the confronting faces of the arms 7, 7 15 of the jaws thereby swinging the jaws to open position, scissors fashion, against the action of the spring 20. As the jaws are swung to open position the hooks 11, 11 release the keeper 13 thereby permitting the 20 door to be slid to open position. The key is given further turning movement so that the same may be withdrawn from the key hole in the casing and in such further movement the cam is restored to initial position 25 thereby permitting the spring to react and throw the jaws to normal.

While I have herein shown and described one preferred form of my invention by way of illustration, I wish it to be understood 30 that I do not limit or confine myself to the precise details of construction herein described and delineated, as modification and

variation may be made within the scope of the claim without departing from the spirit of the invention.

35

I claim:

In a sliding door lock, jaws pivoted upon a common center, scissors fashion, and movable to open and closed positions and each comprising arms offset from each other and a hub interconnecting said arms and formed with a bore adapted to align with the bore in the other hub, a pivot bolt passed through said aligning bores, a cam mounted between the arms of said jaws and adapted to be 40 rotated to swing the jaws to open position, a spring connected to the remaining arms of the jaws and holding the latter in closed position, a shank on said cam, a U-shaped yoke extending over the cam end of said 45 arms, a barrel fixed to the interconnecting member of said yoke and extending outwardly therefrom coaxial with said shank and receiving the latter, hooks formed on the confronting faces of the spring actuated 50 arms of the jaws, and a keeper adapted to be engaged by said hooks.

In testimony whereof I affix my signature in presence of two witnesses.

THADDEUS A. SPRADLEY.
